UNITED STATES PATENT OFFICE.

CHARLES W. BOARDMAN, OF PAWTUCKET, RHODE ISLAND.

TENSION-PULLEY FOR SPINDLE-DRIVING MECHANISM OF TEXTILE-SPINNING MACHINES, &c.

1,148,745.

Specification of Letters Patent. Patented Aug. 3, 1915.

Application filed September 17, 1914. Serial No. 862,158.

To all whom it may concern:

Be it known that I, CHARLES W. BOARDMAN, a citizen of the United States, residing at Pawtucket, in the county of Providence and State of Rhode Island, have invented certain new and useful Improvements in Tension-Pulleys for Spindle-Driving Mechanism of Textile-Spinning Machines, &c., of which the following is a 10 specification.

My invention relates to textile-spindle driving mechanism and particularly to the construction of tension pulleys, so-called, capable of being employed in connection 15 with such driving mechanism.

The object of the invention is to minimize the weight of the pulley and cost of construction and increase its efficiency, the latter being largely due to a reduced degree of 20 centrifugal force and a corresponding saving in the power usually required for rotating tension pulleys as heretofore devised.

In the accompanying sheet of drawings Figure 1 represents a side elevation of a 25 tension pulley embodying my improvements, portions of the pulley being broken away; Fig. 2 is a transverse sectional view, in enlarged scale, taken substantially on line 2—2 of Fig. 1; and Fig. 3 is a similar sectional view showing the members in position immediately preceding the act of joining or securing them together to produce the pulley.

In my improved tension-pulley A, all the 35 members thereof (except the center arbor or axle) are formed of suitable, comparatively thin sheet metal, as steel, having a degree of resiliency, swaged or shaped to the desired form. The said arbor, B, is provided with 40 end journals b¹, b¹, and a central portion b, the latter having any suitable form cross-sectionally. In the drawing the part b is represented as polygonal or square.

The sheet metal members composing the 45 major part of the pulley are as follows: a indicates the circular flat centrally apertured disk supported on the arbor, the axis of the latter being perpendicular to the plane of the disk. If desired the central 50 portion of the disk may be strengthened by one or more lateral reinforcing members a¹. A sheet metal band c snugly encircles the outer peripheral edge of the disk. The band is positioned transversely centrally of 55 the disk and is bent so as to give a slightly

crowning effect to the face of the pulley; this annular band also serves to reinforce the rim portion of the pulley; the ends of the band abutting each other. See a¹. The two outer circular side sections or cheeks d, 60 d of the pulley are formed of sheet metal and given the desired shape by stamping or by other suitable means. The sections d are alike in form and oppositely disposed and arranged to inclose the said disk and 65 band members between them. Each side section is provided with an integral central or hub portion d¹ and an integral circular rim part d², the latter being crowned or beveled transversely to conform to the band 70 c. The inner peripheral edges f f of the rim part of the sections are adapted to engage each other and form the smooth circular joint or seam f¹, indicated in Fig. 2. The said hub portion of the sections may 75 be stiffened by the employment of washer-like members d² secured thereto.

In assembling the parts, assuming the disk a to be provided with the reinforcing band c and also positioned on the arbor B, substantially as represented in Fig. 3, the manner of completing the tension pulley is as follows:—The two side sections d are placed in opposition on the respective end portions of the arbor and forced toward 85 each other in the arrow directions x; at the same time the inner faces of the hub portions engage shoulders b² of the arbor and the inner edges f of the respective circular semi-rims to snugly engage each other; in 90 order to overcome the natural resiliency of the metal the sections are then pressed or clamped so as to spring the flattened sides snugly against the adjacent surfaces of the center disk a, substantially as shown in Fig. 95 2; while thus confined the members a and d d are rigidly secured together in any suitable manner, as for example, by electric spot welding or riveting, etc., thus completing 100 the pulley.

In my improvement the plane substantially flat portions of the side sections and the intermediate or central disk are arranged to be rigidly secured together and form the web part of the pulley, thus stiffening and strengthening it both laterally and torsionally. In some cases the reinforcing or lining band c may be omitted, if desired.

It may be stated that in spindle driving 110

mechanism for textile spinning, twisting and winding or spooling machines my improved tension pulley is well adapted to be advantageously employed. The pulley is formed of sheet metal, therefore its weight is correspondingly reduced; it is practically self-balanced; the pulley, owing to its materially reduced weight, as compared with cast metal tension-pulleys, and even when running at a comparatively rapid speed, is capable of being actuated with less power, thereby increasing the efficiency of the pulley.

It is to be understood that the form and arrangement of the sheet metal elements herewith described illustrate a preferred example of those parts of my improved tension pulley, and that changes in the shape, size and arrangement of parts may be made therein without departing from the spirit of the invention embodied in the subjoined claims.

I claim as my invention:—

1. As an improved article of manufacture, a tension-pulley of the character described, comprising a central axle, a circular disk of sheet metal mounted on the axle, an annular band of sheet metal snugly encircling the peripheral edge of said disk transversely, and a pair of oppositely disposed swaged or pressed outer circular side sections formed of sheet metal, said sections secured to the circular disk and confining it and the metal band therebetween, and having the said axle extending centrally through the side sections.
2. A revoluble tension-pulley consisting of a pair of shaped opposed circular side or cheek sections formed of sheet metal, each section having a central hub portion and a chambered peripheral rim part, the adja-

cent edges of the rim part abutting and forming the transverse face of the pulley, a circular disk of sheet metal positioned laterally between the circular side sections and rigidly secured to them, a relatively narrow band of sheet metal, said band snugly engaging the adjacent circumferential face of the disk and the inner surface of the peripheral rim of the side sections and being inclosed in the chambered portion of the rim, and a journaled axle extending through the center of the said disk and side sections.

3. In a tension-pulley of the character described, the combination of a circular disk, a strengthening or reinforcing band arranged transversely of said disk and snugly encircling it, a pair of exterior parallel circular side sections registering with each other and having their outer peripheral edges constructed to form a surface adapted to carry a belt and also forming an inclosed space or chamber in which said disk and its reinforcing band are confined, means securing the members together, said disk, band and side sections being formed of suitable sheet metal, and a journaled axle or arbor having said members mounted thereon.

4. A tension pulley comprising a pair of side sections having central hub and peripheral rim portions, said sections formed of sheet metal, a disk, also of sheet metal, positioned concentrically between and rigidly secured to the side sections, and an arbor or axle having the said sheet metal members mounted thereon.

In testimony whereof I have affixed my signature in presence of two witnesses.

CHARLES W. BOARDMAN.
